UNITED STATES PATENT OFFICE.

MARIE J. RUSSELL, OF CHICAGO, ILLINOIS.

EYEGLASS-HOLDER.

No. 818,297.

Specification of Letters Patent.

Patented April 17, 1906.

Application filed November 20, 1903. Renewed September 22, 1905. Serial No. 279,711.

To all whom it may concern:

Be it known that I, MARIE J. RUSSELL, a citizen of the United States, residing at Chicago, in the county of Cook and State of Illinois, have invented certain new and useful Improvements in Eyeglass-Holders; and I do hereby declare the following to be a full, clear, and exact description of the invention, such as will enable others skilled in the art to 10 which it appertains to make and use the same.

This invention relates to improvements in eyeglass-holders, and particularly to holders which are capable of use in connection with 15 the hair, the holder being formed in the shape of a hair-pin, capable of use not only for holding the glasses in the hair, but for holding the hair in position in connection therewith.

The invention consists in an eyeglass-holder comprising a hair-pin and means suspended therefrom upon which the glasses may be hung when not in use.

It also consists in a combined hair-pin and eyeglass-holder comprising a hair-engaging 25 portion, a hook loosely secured thereto, and a chain or other flexible connection for securing the eyeglasses to the hook, the said hook also serving to engage the bow or other portion of the glasses for supporting them 30 when not in use.

It also consists in certain other novel constructions, combinations, and arrangements of parts, as will be hereinafter fully described and claimed.

In the accompanying drawings, Figure 1 is 35 a view of the head of a person, showing the hair-pin and eyeglass-holder forming the subject-matter of the present invention secured to the hair. Fig. 2 is a perspective view of 40 the combined pin and glass-holder. Fig. 3 is a similar view showing the pin with two straight prongs.

The invention is designed to supply the need for a device which can be used to suspend 45 eyeglasses from the head of a wearer, the said eyeglasses not depending in any way upon the wearing-apparel of the user, since the glasses when not in use are suspended upon the head.

In giving the invention a practical form I 50 employ a hair-engaging member or pin 1, which is provided with an eye or loop 2, from which is pivotally suspended a hook 3. The pin portion 1 may be made with a single 55 straight prong 4 and a prong 5, which is provided with a bent end portion 6, forming a

hook for engaging the end of the straight prong 4. In placing the pin in the hair the straight prong can be pushed into the hair and the hook 6 of the other prong then 60 brought into engagement therewith for surrounding a portion of the hair and binding the pin firmly upon the same. If desired, however, the pin portion may be formed with two straight prongs, as 7, (shown in Fig. 3,) 65 in which instance the hair-pin is merely thrust longitudinally into the hair. In this instance also the pin portion is formed with an eye or loop 8, from which a hook 9 is suspended. The eyeglasses are connected 70 with the hook by a cord, chain, or other flexible means, as 10, so that if the eyeglasses become accidentally displaced from the nose of the wearer they will not fall and be broken. The cord or chain may be provided with a link or ring 11 at one end, which can be slipped upon the hook of the pin for securing it thereto. The hook 3 or 9 performs the double function of holding the cord or 75 flexible connection with the glasses and suspending means upon which the glasses may be suspended at one end. When the hook is used for supporting the glasses, the bow of the glasses is passed over the hook, or the hook may be made to engage the eye or loop at one 80 end of a pair of glasses, as desired.

The hair-pin may be made of a simple and ordinary form, or the outer bar 5 when the clasp form of pin is employed may be ornamented or provided with stones of various 85 kinds and permitted to show outside the hair. If the pin is not made ornamental, it may be arranged so as to be covered by portions of the hair, if preferred. The hook carried by the pin may be ornamented also or 90 made plain, as found most desirable.

In using the device the hair-pin is properly secured in the hair of the wearer, so that the pendent hook is within easy reach of the hand of the wearer. The flexible connection 100 with the glasses is made of sufficient length to reach from the pin to the nose of the wearer, as illustrated in dotted lines in Fig. 1. When the glasses are not being used, the wearer places the same upon the hook, as 105 shown in full lines in Fig. 1. By this means the glasses may be suspended upon the person of the wearer and yet be entirely free and independent of the clothes or wearing-apparel of the person. The clothes may be 110 changed without disturbing the position of the glasses or without danger of knocking

them from their suspended position. The pin and the hook are capable of economical production or may be made as ornamental and expensive as desired.

5 Having thus fully described my invention, what I claim as new, and desire to secure by Letters Patent, is—

1. An eyeglass-holder, comprising a hair-pin, and a pendent open hook loosely connected therewith and free to swing in all directions, whereby said hook can hang in a vertical position regardless of the position assumed by said hair-pin.

15 2. An eyeglass-holder, comprising a hair-pin, an eye formed thereon, a pendent open hook, and an eye formed on said hook interlocking with the eye of said pin permitting the hook to always hang in a vertical position.

3. An eyeglass-holder for the hair comprising a hair-pin having a loop at one end forming an eye, a clasp at the other end of the hair-pin, a pendent hook having an eye for engaging the eye of the pin, the upper end of the hook being open for receiving eyeglasses, the connection formed by the eye of the hook with the eye of the pin permitting of the pin hanging in a vertical position at all times when the hair-pin is in place in the hair of the user.

In testimony whereof I hereunto affix my 30 signature in presence of two witnesses.

MARIE J. RUSSELL.
